AMPLIFYING SYSTEM

Filed Sept. 21, 1928

Inventor:
Thomas H. Kinman,
by Charles E. Tullor
His Attorney.

UNITED STATES PATENT OFFICE

THOMAS H. KINMAN, OF BILTON, RUGBY, ENGLAND, ASSIGNOR TO GENERAL ELECTRIC COMPANY, A CORPORATION OF NEW YORK

AMPLIFYING SYSTEM

Application filed September 21, 1928, Serial No. 307,474, and in Great Britain October 10, 1927.

The present invention relates to amplifying systems which include electric discharge devices and are particularly intended for the amplification of high frequency electric oscillations.

The object of the invention is to simplify the operations necessary for the adjustment of a high frequency amplifier so that it may be especially suitable for incorporation in a radio receiving system adapted to receive alternatively on a number of specified wave lengths or frequency channels.

In accordance with the invention, an amplifying system of the above-named type for high frequency oscillations is rendered simultaneously selective to oscillations of two or more predetermined frequencies. In order to obtain this result, the anode circuit of one or more of the electric discharge devices employed, which may be ordinary receiving vacuum tubes, for example, is rendered selective to the predetermined frequencies by including therein a plurality of circuits tuned to the various frequencies it is desired to select, the constants and arrangement of each tuned circuit being such that it affords a negligible impedance to oscillations of the frequencies to which the other circuits are tuned.

In carrying the invention into effect, I preferably employ tubes of the type now commonly known as "screen-grid" tubes, that is to say, tubes having the usual cathode, anode and control grid and provided, in addition, with a screen grid located between the control grid and the anode, the purpose of which is to eliminate the inter-electrode capacity which would otherwise exist between the control grid and the anode. Two or more inductances connected in series or in parallel in the anode circuit of the tube are tuned to the frequencies it is particularly desired to amplify. The tuned circuits are so designed that whichever frequency is being amplified, one of the tuned circuits offers a high impedance to that frequency, while the remaining tuned circuits offer little or no impedance to that frequency. That is to say, the remaining tuned circuits freely pass oscillations of a frequency other than that to which they are

specifically tuned. By a suitable coupling device, the voltage pulsations set up across the circuit tuned to the frequency being amplified is transferred to the grid of the next tube in the system, which may be another amplifying tube, or means arranged to detect the high frequency oscillations.

The input circuit of the first tube of the system is preferably coupled to, or associated with, an antenna or like receiving device for the high frequency oscillations, the antenna or input circuit being tuned to the frequency it is desired to receive and to amplify selectively.

The arrangement in accordance with the present invention although not limited thereto, is particularly adapted for use with an antenna, or like receiving device, arranged to receive on alternative wave lengths in the manner described in my copending application, Serial No. 219,083, filed September 12, 1927. The tuned circuits situated in the anode circuits of the tubes are then tuned to the same frequencies as those to which the antenna or input circuit is tuned, and when oscillations of either of the selected frequencies are received, they are selectively amplified in the system. Any adjustment is unnecessary other than those adjustments made when the circuit arrangement is first assembled.

My invention will be better understood from the following description when considered in connection with the accompanying drawing and its scope will be pointed out in the appended claims.

In the accompanying drawing is diagrammatically illustrated a typical receiving circuit including two high frequency amplification stages arranged in accordance with the invention and utilizing electric discharge devices of the screened grid vacuum tube type.

Referring to the drawing, a signal receiving device 5, provided in the present example with an inductance 6 coupled with an antenna 7 by a coil 8, is connected to the filament and control grid of the first tube 9, and is shunted by two condensers 10 and 11 in parallel, the condenser 11 having a switch 12

arranged to connect and disconnect it. When the aforesaid condenser 11 is disconnected, the remaining condenser 10 tunes inductance 6 to one of the frequencies it is desired to receive whereby the signal receiving device is responsive to that frequency or signals of that frequency. On connecting in the condenser 11 the increased capacity obtained is of such value as to tune inductance 6 to the other frequency it is desired to receive whereby the input or receiving device is responsive to the latter frequency. The receiving device is thus rendered selectively responsive to each of said predetermined frequencies separately. Obviously the receiving device 5 may be replaced by any other suitable form of signal receiving device capable of being tuned, such as a loop antenna for example, which inductance 6 alone may be taken to represent.

The anode circuit of the tube 9 contains two tuned circuits 13—14 and 15—16 in series, each consisting of an inductance and capacity in parallel, 13 and 15 being the inductances and 14 and 16 their respective tuning capacities. The resonant frequencies of these two tuned circuits correspond respectively with the frequencies to which the signal receiving device is capable of being tuned. These frequencies should preferably be separated by a fairly wide margin, whereby a response to a band of frequencies is prevented, and when employed for the reception of broadcasting, may correspond with the frequencies of a main station and another high power, long wave station, for example. The constants of the tuned circuits in the anode circuit are so arranged that at the frequency to which one of them is tuned, the condenser of the remaining tuned circuit constitutes a low impedance for that frequency, and vice versa. The potential variations set up at the terminals of the tuned circuits are transferred from the high potential end of the anode circuit to the grid of the next tube 17, which may be a detector or another amplifier, but which in the arrangement shown is a second amplifier, through the usual single coupling capacity 18, and a resistor 19 is provided for applying a biasing potential to the grid of tube 17. The connection from the end of the tuned circuits 15—16, remote from the anode, to the anode supply source (not shown) is made in the usual manner through a suitable supply lead 20, and the screening grid is connected to a source of suitable voltage (not shown) through a supply lead 21.

The connections of the second amplifying tube 17 are arranged in a similar manner, the anode circuit being tuned to the two predetermined frequencies by means of circuits 22—23 and 24—25, and the anode potential variations therefrom are passed on to a following tube or other receiving device,

through a second coupling condenser 26, and a grid biasing or load resistor 27 is connected across the output circuit which is indicated at 28.

The coupling between each of the tuned anode circuits and the succeeding tube or device may be obtained in other ways, for example, through tuned circuits similarly associated in the grid circuit of the following tube, which are coupled respectively to the tuned circuits situated in the anode circuit of the preceding valve.

Likewise one skilled in the art will readily appreciate that the tuned anode circuits may similarly be arranged in parallel, instead of in series as described, one tuning condenser only being employed to tune the two inductances. Similarly, in the series arrangement described, the tuning condenser for the shorter wave may be eliminated with proper design of the inductance. Thus inductances 13 and 22 may be wound in the form of aperiodic radio-frequency chokes, so that they will respond to a definite or predetermined wave band, such as the broadcast band from 200 to 500 meters, while 15 and 24 may be tuned by fixed or variable condensers 16 and 25 to any longer wave length, as previously described.

It has been found that the use of screen-grid tubes assists in the application and successful operation of the amplifier, although it is desired to point out that the benefits of the invention can be obtained with other suitable tubes such as the more usual three-electrode type.

It is desirable that each stage of high frequency amplification, with its associated circuits, should be effectively screened from its neighbor and all external influences. This may be done by suitable metal enclosures or shields now commonly known and used.

A receiver or amplifier arranged in accordance with the invention is advantageous inasmuch as reception and amplification is possible on a plurality of alternative wave lengths without any adjustment other than the operation of a simple switching device, which is incorporated in the input or other tuned receiving circuit, as hereinbefore referred to. No adjustment of the amplifier itself is necessary.

It will also be evident that, although the provision of two tuned circuits in each anode circuit of the tube has been specifically referred to in the present example, more than two tuned circuits may be employed if desired, thereby rendering the arrangement selective to more than two predetermined frequencies.

What I claim as new and desire to secure by Letters Patent of the United States, is:—

1. In a high frequency signal amplifying system employing a plurality of electric discharge devices, a plurality of circuits tuned

to different predetermined frequencies and included in a single anode circuit of one of said devices, said frequencies being separated to prevent band pass tuning in said circuit,
5 the constants of each tuned circuit being such that it produces a negligible impedance drop when subjected to oscillations of frequencies to which the other circuits are tuned and produces a high impedance drop when subjected
10 to the frequency to which it is tuned, a single coupling means connected with the high potential end of the anode circuit and with the control electrode of a second electric discharge device, and selector means for selectively introducing into said system a signal
15 of any one of said predetermined frequencies.

2. In a radio frequency amplifier including two electric discharge devices, the combination of a signal receiving device, means for selectively tuning said receiving device separately to each of a plurality of relatively widely separated predetermined frequencies, and a single tuned circuit introduced between said electric discharge devices and connected
25 with the anode of the one and the grid of the other, said circuit being arranged to respond to any of said predetermined frequencies and including a series of tuned inductance units each tuned to a different one
30 of said predetermined frequencies.

In witness whereof, I have hereunto set
my hand this fourth day of September, 1928.

THOMAS H. KINMAN.
